UNITED STATES PATENT OFFICE.

HIPPOLYTE MARIUS CHIRON AND FREDERIC PARME, OF NEW YORK, N. Y.

LIGATURE FOR CLARINET AND SAXOPHONE MOUTHPIECES.

Application filed January 31, 1923. Serial No. 616,128.

To all whom it may concern:

Be it known that we, HIPPOLYTE MARIUS CHIRON, a citizen of France, and FREDERIC PARME, a citizen of the United States, residing in the city of New York, county of New York, and the State of New York, have invented a new and useful Improvement in the Ligature for Clarinet and Saxophone Mouthpieces, of which the following is the specification, to wit.

This invention relates to improvements in mouthpieces, and the main object is to provide a ligature for clarinet and saxophone mouthpieces, by which greater amplification of sound vibrations of the reed is received.

We attain this effect by the means that are illustrated in the accompanying drawing in which,

Fig. 1 is front side view of the rubber isolator.

Fig. 2 is the front bottom view of the isolator.

Fig. 3 is the front side view of the ligature.

Fig. 4 is the front side view of the ligature with the isolators adjusted.

Fig. 5 is the front view of the ligature mounted in place on a cross section of the mouthpiece, with isolator and section of the reed, in place.

1 is the head of the isolator. 2 is the perforation. 3 is the body of isolator. 4 are the teeth on bottom of isolator. Fig. 2. 5 are the two rings of ligature. Fig. 3. 6 are the two sides of ligature holding the ring 5 in place. 7 are the sockets, on each side of rings 5, to receive thumb-screws 8. 9 is a cross section of the reed. 10 is a cross section of the mouthpiece.

Similar numerals refer to similar parts throughout the various drawings.

With the present type of ligature the vibrations in clarinet and saxophone reeds are dulled and restrained. This is due to the fact that the two rings of the ligature, being made of metal, hold the reed so tight

when in place that but little vibration is possible. With our improved ligature however, the vibration of the reed can be greatly increased by adding isolators, made of rubber or some other soft material. The isolators contact with the reed and the rings of the ligature retain said isolators in place.

The general operation of our ligature is the same as any other ligature, with the exception of the isolators. These are held in place by putting the head 1 between the sockets 7 on each side of the rings 5 so that thumb-screws 8 will pass through perforation 2. Thus the main body of the isolator comes under the metal rings 5 as shown in Fig. 4. Having adjusted the isolators place the ligature over the reed 9 and mouthpieces 10 so that the teeth 4 of isolator 65 will come into contact with the reed 9. Tighten thumb-screws 8 any amount desired to produce the vibration satisfactory to the player.

We claim:

A ligature for clarinet and saxophone mouth pieces comprising a pair of split rings, side members joining said rings, lugs rigid on the split ends of said rings and provided with sockets, said lugs being arranged in pairs, one lug of each pair having a threaded opening, the opposite lug having a plain opening, each pair of lugs having a space therebetween, an arcuate body having a projection thereon, said projections being adapted to be inserted between the pairs of lugs and each projection having an opening therein adapted to align with the openings in the lugs, teeth on the lower surface of said arcuate body extending laterally of the rings, said teeth being adapted to contact with the surface of a reed on the clarinet or saxophone, and a thumb screw passing thru each pair of sockets and the opening in each projection of the body for retaining said body in place above the reed.

HIPPOLYTE MARIUS CHIRON.
FREDERIC PARME.
